[57] **CLAIM**

The ornamental design for a housing for electronic instructional game apparatus, as shown and described.

DESCRIPTION

FIG. 1 is a front elevational view of the housing for electronic instructional game apparatus, showing my new design;

FIG. 2 is a right elevational view thereof;

FIG. 3 is a left elevational view thereof;

FIG. 4 is a rear elevational view thereof;

FIG. 5 is a top plan view thereof; and,

FIG. 6 is a top perspective view thereof.

The broken lines shown in FIGS. 1, 2, 3, 5, and 6 are for illustrative purposes only and form no part of the claimed design.

The bottom is substantially plain and unornamented.
